(57) **CLAIM**

The ornamental design for a removable face pack for an electronic irrigation controller, as shown and described.

DESCRIPTION

FIG. 1 is a front perspective view of a removable face pack for an electronic irrigation controller showing my new design.

FIG. 2 is a rear perspective view thereof.

FIG. 3 is a front elevational view thereof.

FIG. 4 is a rear elevational view thereof.

FIG. 5 is a left-side elevational view thereof.

FIG. 6 is a right-side elevational view thereof.

FIG. 7 is a top plan view thereof; and,

FIG. 8 is a bottom plan view thereof.

Broken lines throughout the drawings indicate environmental elements, such as labels, a reset button, a cable receptacle, a battery access door, a battery, clearance slot, and screw holes, that form no part of the claimed design.
